UNITED STATES PATENT OFFICE.

THURMAN J. BIXLER, OF HUTCHINSON, KANSAS.

COOLING AND DISPENSING CABINET.

Application filed August 13, 1926. Serial No 129,030.

This invention relates to a cooling and dispensing cabinet for use in cooling and dispensing bottled beverages or liquids, and one object of the invention is to provide a cabinet 5 having a cooling chamber and one or more U-shaped racks forming channeled runways contained therein for holding the bottles to be cooled, said runways being so constructed as to adapt the bottles to roll by gravity there-through between inlet and delivery ends thereof for a free and easy automatic dispensing action.

Another object of the invention is to provide racks or runways of unitary construction 15 independently insertable for use and removable for cleaning or repairs, and each having a plurality of runway channels so that a large number of bottles may be stored within a cabinet of convenient size.

Still another object of the invention is to provide racks or runways which are imperforate and exclude ice or water from the runways and from coming in contact with the bottles and interfering with their free travel 25 or damaging the labels or otherwise rendering the bottles unsightly or unsuitable to handle as dispensed.

Still another object of the invention is to provide a construction of cabinet which 30 affords free access at all times to the cooling chamber and runways so that all parts may be reached for insertion of ice and insertion and removal of bottles, as well as for repairs and maintenance of the cabinet in a highly 35 sanitary condition.

The invention consists of the features of construction, combination and arrangement of parts, hereinafter fully described and claimed, reference being had to the accompanying drawing, in which:—

Figure 1 is a front view of the cabinet.

Figure 2 is a side view thereof.

Figure 3 is a vertical transverse section on line 3—3 of Figure 4.

Figure 4 is a vertical front-to-rear section on line 4—4 of Figure 3.

Figure 5 is a horizontal section on line 5—5 of Figure 4.

In carrying my invention into practice, I 50 provide a cabinet or enclosing casing 1, of rectangular, oblong rectangular or other suitable form, and constructed of wood, metal or any desired combination of these materials. This casing incloses and provides a cooling 55 chamber 2, designed to contain a suitable cooling medium, such as ice, a cooling liquid,

or a refrigerating coil or the like. This chamber is provided with a wall or lining 3, of copper or other suitable metal or material, between which and the walls of the cabinet 60 body is a filling or layer 4 of cork or any other suitable insulating or heat non-conducting material.

Enclosed within the cabinet, and disposed within said cooling chamber 2, is a series of 65 bottle-holding racks or runways 5, three of such racks or runways being shown in the present instance, although it is to be understood that the number may vary as desired, according to the size and designed capacity 70 of the cabinet. These racks or runways, as shown, are arranged side by side, in parallel relationship to each other, and preferably slightly separated from each other and the walls of the cooling chamber, so as to permit 75 all surfaces of the racks lying in the cooling zone to come in contact with the cooling medium.

Each rack or runway 5 is of unitary construction and made of some good conducting 80 material, and each rack is preferably U-shaped, or substantially so, so as to provide a vertical intake arm 6, a vertical outlet or discharge arm 7, and a curved or return portion 8 connecting said arms at their lower 85 ends. The racks may rest directly at their bases upon the bottom of the cooling chamber 2 and be loosely disposed in the cabinet, or detachably held in position in any suitable manner, so that the racks may be independently applied and removed, allowing 90 cleaning, repairs or replacements to be made in a ready and convenient manner, so that the cabinet and all of its contained parts may be kept in thorough working order and in a thoroughly sanitary condition at all times. 95

The upper ends of the arms of the racks lie at a level, which may be above the horizontal level of the cooling medium, and preferably in close proximity to the upper open top of the cabinet, the arrangement thus being such that the bottles or containers 9 may be inserted from above down into the intake arms of the racks and discharged from the outlet arms of the racks through the open top of the casing. 100 When the racks are in position in the cooling chamber, the spaces between their vertical arms and above their bases are in alinement and form a compartment normally communicating with the open top of the cabinet, into 110 which compartment the ice, if such a refrigerant is used, may be inserted. Ice in crushed

form, if desired, may be employed so that the racks or runways may be fully embedded therein, or ice and water or brine in suitable quantities may be employed, in cabinets up to 5 a reasonably large size, in the absence of or when it is not desired to employ mechanical refrigerating means. A single cover may be employed to normally close the open top of the container, but in the present instance a 10 cover composed of three cover sections 10, 11 and 12 is shown, the cover section 10 closing access to that part of the cooling chamber between arms of the racks, the cover section 11 closing access to the inlet ends of the racks 15 and the cover section 12 closing access to the delivery or discharge ends of the racks, thus permitting access to the racks for filling and dispensing purposes without removing the closure affording access to the cooling chamber. 20

In accordance with my invention, each rack is imperforate, or closed at all points except at its intake and discharge ends, in order to prevent access of the cooling liquid and ice to 25 the interior of the racks. By this means the surfaces of the bottles will always be kept dry and in presentable condition and in proper condition for handling, and damage to the bottle labels will also be avoided. Each 30 rack 5 also provides a bottle containing runway channel or channels which is or are flat in cross-section so as to hold the bottles in a horizontal position for rolling engagement with the walls of the channel or channels. By 35 this means a free and easy running motion of the bottles in the channel is secured, defacement of the labels or stoppers of the bottles prevented, and liability of clogging of the bottles in the channels obviated. It is to be 40 understood that the bottles to be cooled are inserted into the intake ends of the racks for a gravity feed through the racks and automatic discharge from the rack at their discharge ends. Initially, the channels of the 45 racks are completely filled, so that a balanced weight of the bottles in the inlet and outlet ends of the rack arms will be obtained, whereby, upon the placing of another bottle above the top one at the inlet end of the rack, the 50 weight of the bottles in the inlet end of the rack will be greater than those in the outlet end of the rack, causing a movement of the

bottles through the rack and the discharge of a bottle at the outlet end of the rack following the insertion of each bottle at the inlet end of 55 the rack. By disposing the bottles in a horizontal position, instead of in a vertical position, a rolling feed action is obtained, as above-described, and a greater number of bottles may be placed in each rack of a cabinet of 60 a given height, while at the same time a more positive and certain feed action is secured, and, by such construction also the necessity of employing an overhead rack to give a very great preponderance of weight to the bottles 65 in the inlet arms of the racks, or the necessity of employing a forcing pressure on the bottles, as is necessary when the bottles are vertically disposed, is entirely overcome. I also 70 preferably provide each rack with a partition 13, thus subdividing the rack into two channels, thereby increasing the capacity of the rack and providing for the storage of bottles containing different liquids or bottles of different sizes containing the same liquid in one 75 and the same rack. The partition also serves to stiffen the rack and to provide a stronger construction.

In the use of ice, ice and water, or ice and 80 brine as a refrigerant, the cabinet may be provided at its bottom with a drain cock 14 for an obvious purpose.

Having thus fully described my invention, I claim:—

A combined refrigerating and dispensing 85 apparatus comprising a cabinet having a refrigerant containing chamber, and a series of U-shaped dispensing racks disposed in said chamber and independently insertable therein and withdrawable therefrom, each rack being 90 of unitary formation and of non-circular form in cross-section and comprising imperforate top, bottom and side walls, whereby the racks are closed against communication with the refrigerant containing chamber of the cabinet, 95 each rack having a transverse partition dividing it into upper and lower bottle containing channels, and said racks being arranged with their adjacent sides in spaced relation to each other for the flow of the refrigerant between 100 them.

In testimony whereof I affix my signature.

THURMAN J. BIXLER.
